PROTECTIVE TAIL WRAP FOR HORSES

Le Roy J. Hyman, Del Jay Farm, Chagrin River Road,
Gates Mills Village, Ohio 44040

Filed Jan. 16, 1967, Ser. No. 5,445

Term of patent 14 years

(Cl. D30—37)

The broken lines shown on the tail wrap in FIGS. 1, 2 and 3 on the drawing represent conventional stitching.

I claim:

The ornamental design for a protective tail wrap for horses, substantially as shown and described.
